2 Sheets-Sheet 2

The diagram shows a large rectangle divided into several sections. The top section is labeled "END" on the left and "ZONE" on the right. The bottom section is labeled "ZONE" on the left and "END" on the right. The left and right edges of the rectangle are marked with a series of numbers from 0 to 20 in increments of 0.5. The top and bottom edges are also marked with a series of numbers from 0 to 20 in increments of 0.5. There are several labels and symbols within the rectangle: "GOAL" is at the top center, top right, and bottom center; "END" is at the top left, bottom left, and bottom right; "ZONE" is at the top right, bottom left, and bottom right; and "20" is at the top left, top right, bottom left, and bottom right. There are also several small circles with numbers inside them, such as "21", "22", "23", "24", "25", "26", and "27", scattered throughout the field.

Technical drawing of a cross-section of a rectangular structure, labeled "Fig. 3." The drawing shows a central rectangular frame with various dimensions labeled in inches. The top edge is 20 inches long, with a 6-inch gap at the top right corner. The left edge is 18 inches long, with a 6-inch gap at the bottom left corner. The right edge is 20 inches long, with a 6-inch gap at the top right corner. The bottom edge is 18 inches long, with a 6-inch gap at the bottom left corner. A small rectangular cutout is located in the upper right quadrant of the frame. The entire structure is surrounded by a thick, hatched border.

UNITED STATES PATENT OFFICE

EUGENE W. ROBERT, OF ATLANTA, GEORGIA

FOOTBALL GAME

Application filed February 24, 1928. Serial No. 256,736.

My invention relates to an improved apparatus adapted for use in playing a game in imitation of a regulation football game.

The primary object of the invention is to provide an improved apparatus suited to playing an imitation game along lines closely related to the plays in actual football games.

A more specific object is to provide an improved chance device for use in determining the successive plays made and the results of such plays.

The invention consists in the novel form, combination and arrangement of parts hereinafter more fully described, shown in the accompanying drawings and claimed.

In the drawings:—

Figure 1 is an enlarged plan view of a chance device forming parts of the game apparatus embodying the present invention.

Figure 2 is a fragmentary plan view of the game board, showing the representation of a football field.

Figure 3 is a transverse section of the complete board; and

Figure 4 is an enlarged perspective view of a game piece which may be employed on the game board to indicate the position of the ball in play.

Referring more in detail to the drawings, the present game apparatus embodies a chance device 5 for use in determining the successive plays made and the results of such plays, a game board having therein the chance device 5 and the representation 6 of a football field, and a game piece 7 for use on the board to indicate the position of the ball in play on the field.

The chance device 5 preferably consists of a sheet formed of carboard or other suitable material and having inscribed thereon a plurality of concentric circles 8, 9, 10, 11, and 12 defining a plurality of circular areas therebetween and a central circular area within the innermost circle. As shown, the central circular area is subdivided by radial lines 13 into spaces inscribed with legends designating different results of kick-offs made when starting play. The circular area between the two outermost circles is divided by radial

lines 14 into spaces inscribed with legends designating different results of plays made in receiving the ball from kick-offs. Radially aligned spaces of these two areas are, in playing the game, to be read jointly in determining the ultimate result of a kick-off and the position to be assumed by the game piece when play is resumed. These areas are accordingly given similar visible characteristics, such as being of the same color as shown by the shade lines. The circular area between the two innermost circles is divided by radial lines 15 into spaces inscribed with legends designating different results of running plays, and the next outer circular area is divided by radial lines 16 into spaces inscribed with legends designating different kinds of running plays. Radially aligned spaces of these latter two areas are to be read jointly in determining the character and result of a running play when the player elects to make a running play after kick-off, and such areas are accordingly given other similar visible characteristics, such as a common color different from that of the two first-mentioned areas, as shown. The remaining circular area, as shown, has a still different visible characteristic or color, and is divided by radial lines 17 into spaces inscribed with legends designating different results of forward passes. The plays, as they come in the game, are determined by revolving a single pointer 18 which is pivoted to the board at the center of the circular areas of the chance device. A simple and readily readable single chance device is thus provided for presenting in compact and complete form substantially all of the realistic features, plays and results experienced in actual playing of a regulation football game. The only features omitted are the unnecessary and relatively unimportant ones of kicking field goals and kicking goals after touchdowns for extra points.

The board consists of a flat box composed of similar half sections hinged together along adjacent sides as at 19 to permit folding thereof into compact form, and printed or otherwise suitably provided upon the inner surface of one section of the board is the representation 6 of a football field, the chance

device 5 being secured on the inside of the other section of the board. This representation preferably embodies side lines 20, goal lines 21, end lines 22, five yard lines 23 connecting the side lines and numbered as at 5 24 along the latter, one yard lines 25 between the five yard lines, a goal 26 on each end line, and marks 27 on the respective 40 yard lines to designate the positions of the ball for kick-offs.

10 The game piece 7 is used as a marker adapted to be moved to different positions on the surface of the game board as dictated by each use of the chance device, in order to 15 keep account of what yard line the ball is on. As shown, the game piece may consist of a miniature representation of a football carried by a short supporting base or pedestal.

20 The rules for playing "indoor football" are the same as the present rules governing the outdoor game with two exceptions, i. e., the try for field goal or drop kick and the try for extra point after a touchdown.

25 To begin play the opposing players toss a coin and the winner has the choice of receiving the kick or kicking to his opponent. The player kicking then spins the pointer and the legends in the inner and outer circular areas show the results of the kick-off. 30 For instance, if the inner circle reads "touchback" the outer circle reads "return to 20 yard line."

The player who received the kick is then 35 in possession of the ball on his own 20 yard line and the marker is moved from the kick-off line to his 20 yard line. He then has four downs or spins in which to gain ten yards and failure to make this yardage gives possession of the ball to his opponent.

40 A player in possession of the ball has the choice of playing either circular area he wishes but must designate the one he is playing before each spin. If he is playing a line 45 or running play the second outer circle is used, if a forward pass the second inner circle is used, and if he prefers to punt the same circles are read as on the kickoff. The same penalties apply as in the outdoor game.

50 For instance two or more incomplete forward passes in one series of plays for a first down result in five yard penalties.

When a player in possession of the ball has penetrated into his opponent's territory as far as his 20 yard line he has the privilege of trying a field goal or dropkick. To do this he places the ball or game piece on his own ten yard line and attempts to thump it between the uprights of the opponent's goal post. If successful he gains three points and if unsuccessful the opponent has possession of the ball on his twenty yard line.

When a touchdown is scored the side scoring is credited with six points. Then he has one play to try for the one extra point and

may do so as follows: Either place the marker on his opponent's ten yard line and try a running play or forward pass or drop back to his own twenty yard line and try to thump the ball between the uprights of his opponent's goal posts. In either event if successful he is credited with an additional one point, making seven.

70 It is desirable to have someone act as referee and when this is possible the players must abide by his decisions. The game can be played in quarters of a given length of time each, (usually fifteen minutes), or a designated number of plays per quarter, (preferably forty). The referee can serve as time-keeper or keep tally of the number of plays used, as the case may be. He also is final judge of close decisions and keeps records of the down, etc. When the pointer stops exactly on a line in the circle played both teams 75 are ruled offside and the play is repeated without loss of down or other penalty. All punts that go over the defending player's goal line are given into his possession on his own twenty yard line.

80 This game is admirably suited for use in teaching persons who are not well versed in football the fundamentals of the game by explaining why certain plays are used under certain conditions, and at the same time the 85 element of chance enters so strongly into it that a beginner often outscores a veteran football player, although superior knowledge of the game is usually shown by the results.

90 As shown clearly in Figures 1 and 3, the 100 pointer 18 is formed of a narrow strip of metal and has oppositely projecting arms, one of which arms has its plane horizontal, and the other of which arms is twisted at right angles to the first named arm so that its plane is vertical, said other arm constituting a thin straight indicating hand extending to the outermost circle 12 so that the desired chance indication may be readily 105 read in any circular area.

110 The goal posts 26 are in the nature of small upright wickets fastened to the board and of such height that they will not interfere with closing of the latter. Mounted on the end walls of the board section having the representation of the field, are small bells 28. These bells are disposed behind and between the uprights of the goal posts so as to be struck by the game piece when it is thumped between said uprights, thereby giving an 115 audible and unquestionable signal indication when a try for goal is successful.

What I claim as new is:

120 1. In a football game, a game board having a diagram of a football field thereon, goal post-forming wickets mounted in an upright position on the board at opposite ends of the diagram, and signal bells mounted behind and between the uprights of said wickets.

125 2. In a football game, a game board hav-

ing a diagram of a football field formed thereon, goal post-forming wickets mounted in an upright position on the board at opposite ends of said diagram, signal bells mounted beyond and in alinement with said wickets, and an indicator movably mounted on said playing field, said indicator being constructed to represent a miniature football, and being so made as to permit it to be 10 thumped through either of said wickets, from a predetermined position on said field, whereby to ring said bell.

In testimony whereof I affix my signature.
EUGENE W. ROBERT.
